UNITED STATES PATENT OFFICE.

HERMAN WIPE, OF SHARON HILL, PENNSYLVANIA, ASSIGNOR TO JOHN WYETH, FRANK H. WYETH, AND EDWARD T. DOBBINS, OF PHILADELPHIA, PENNSYLVANIA.

DESIGN FOR A BOTTLE.

SPECIFICATION forming part of Design No. 25,640, dated June 16, 1896.

Application filed May 1, 1896. Serial No. 589,910. Term of patent 7 years.

To all whom it may concern:

Be it known that I, HERMAN WIPE, a citizen of the United States, residing at Sharon Hill, in the county of Delaware and State of Pennsylvania, have invented and produced a certain new and original Design for Bottles, of which the following is a specification, reference being had to the accompanying drawing, forming part thereof, and representing in perspective a bottle of my invention.

The leading features of my design consist of the rectangular panels A, extending from the base of the bottle to approximately the middle thereof; the cylindriform neck B, having at the upper and lower edges the rings F; the converging, concave, and substantially trapezoidal panels D, joining the upper edges

of the panels A with the lower ring F of the cylindric neck B; and the concaved meeting edges E of the panels D, forming substantially triangular panels diverging from the panels A to the lower ring F.

Having thus described my invention, what I claim as new, and desire to secure by Letters Patent, is—

The design for a bottle, herein shown and described.

In testimony whereof I have hereunto set my signature in the presence of two subscribing witnesses.

HERM. WIPE.
